UNITED STATES PATENT OFFICE.

JOHN MADDOCK, OF MINNEAPOLIS, MINNESOTA, ASSIGNOR OF ONE-HALF
TO FRANK E. CURTIS, OF SAME PLACE.

BAG.

SPECIFICATION forming part of Letters Patent No. 326,665, dated September 22, 1885.

Application filed October 6, 1884. (No model.)

To all whom it may concern:

Be it known that I, JOHN MADDOCK, a citizen of the United States, residing at Minneapolis, in the county of Hennepin and State of Minnesota, have invented certain new and useful Improvements in Bags; and I do hereby declare the following to be a full, clear, and exact description of the invention, such as will enable others skilled in the art to which it applies to make and use the same.

My invention relates to improvements in the sewed bags which are used for holding flour. These bags are made from burlap or other material that is loose in texture, and they are usually made with a seam across the bottom and up one side. As heretofore constructed these bags have been objectionable, for the reason that under the pressure of the flour in the bag the stitches of the seam would push forward, displacing the fiber of the cloth, and leave a small opening along each side of the seam, through which the flour would sift, thereby causing a great deal of waste.

The object of my invention is to provide a sewed bag that shall be free from this objection, while it is at the same time no more expensive than the ordinary sewed bag.

My invention consists in the bag hereinafter described, and particularly pointed out in the claim.

Figure 1 in the accompanying drawings is a section of a bag made in accordance with my invention. Figs. 2 and 3 are details illustrating the manufacture of the same. Figs. 4 and 5 are sections of a bag made in the common way. Figs. 6 and 7 are views showing material such as is used in the manufacture of these bags. The said several figures are on an enlarged scale. Fig. 8 is a perspective of a bag made according to my invention, it being represented as turned partly inside out to show the folds at the seam.

In the drawings, A, Figs. 6 and 7, represents a piece of burlap, this being the material usually employed in the manufacture of flour-bags. It will be seen that this is a material that is loose in texture. If a row of stitches be run across the material, as indicated by *c* in Fig. 6, and any pressure is applied to this row of stitches in the direction of the arrow in Fig.

6, the threads *b b* of the material, that are substantially parallel with the row of stitches and upon the side opposite that to which pressure is applied, will be crowded together, the stitches *c* and the cross-threads *b b* sliding on the longitudinal threads *a a*, and an opening will be left above the stitches, as indicated in Fig. 7. These figures, together with the above explanation, illustrate the objection that is overcome by my invention. This objection will be more fully understood by reference to Figs. 4 and 5, each of which is a section across the seam of a flour-bag as constructed prior to my invention. The edges of the material that are united to form the seam are each folded back upon itself, as shown in Fig. 4. A row of stitches, *c*, is then passed through the four thicknesses of the material from one-half to three-quarters of an inch from the edges of the folds, or so far from the edges that the bag is subject to the objection herein specified. This row of stitches extends across the longitudinal threads *a a*, at substantially right angles thereto, and substantially parallel with the cross-threads *b b*. This seam is upon the inside of the bag when ready for use, and when the bag is filled with flour the weight upon each side of the seam presses upon the material, and as the loose cross-threads between the stitches and the edges of the folds do not offer sufficient resistance to prevent it, the stitches press along the longitudinal threads, crowding the loose cross-threads aforesaid closely together, and leaving, consequently, an opening behind each stitch. There is therefore a space along each side of the seam, as shown in Fig. 5, at which there are no cross-threads, they having been displaced, and through these openings the flour continually works out.

Figs. 1, 2, and 3 are views which illustrate a bag made in accordance with my invention. The material of which the bag *D* is made is folded back at the edges for about an inch or an inch and a half. This folding of the material causes bends or turns in the longitudinal threads *a a*, as shown in Figs. 1 and 2. The folded edges are brought together, as shown in Fig. 2, and the row of stitches *c* is run through the four thicknesses of the material close to the edges of the folds across the longitudinal

threads *a a*, and in the direction of the cross-threads *b b*. The cross-threads *b b*, that are between the row of stitches and the edges of the folds, are held closely between these stitches 5 and the turns or bends in the longitudinal threads *a a*. The cross-threads are unable to move when the pressure of the stitches comes against them, because the turn or bend in the longitudinal threads prevents any movement 10 on their part, and as they cannot move out of place the stitches are prevented from moving forward out of place, and the opening beside the stitches is thus precluded. The seam will therefore remain tight and firm under pressure, and the bag can be used as safely as a bag 15 constructed without a seam.

The terms "longitudinal threads" and "cross-threads" are used for convenience merely, "longitudinal" being applied to the 20 threads of the material across which the row of stitches extends, and "cross-threads" to those which extend substantially in the same direction as the row of stitches. Threads

which are longitudinal as respects the seam at the bottom of the bag will be cross-threads as respects the side seam, and vice versa. 25

I claim as my invention—

As an article of manufacture, a bag formed of material of loose texture having meeting edges each turned back upon itself, and a row 30 of stitches passing through said folded edges from one fold through the other, said stitches being placed close to the turns, substantially as described, to lock the cross threads or fibers between the stitches and the turns in the longitudinal threads or fibers, and preclude movement of such cross-threads and the stitches, all 35 substantially as described, and for the purposes set forth.

In testimony whereof I affix my signature 40 in presence of two witnesses.

JOHN MADDOCK.
